US0D1107576S

(12) **United States Design Patent** (10) Patent No.: **US D1,107,576 S**
bincan (45) Date of Patent: ** Dec. 30, 2025

(54) **PH TEMPERATURE DETECTOR**

D831,511 S * 10/2018 Blondin D10/56
D1,039,405 S * 8/2024 Li D23/208

(71) Applicant: **Su bincan**, Yangjiang (CN)

* cited by examiner

(72) Inventor: **Su bincan**, Yangjiang (CN)

Primary Examiner — Antoine Duval Davis
(74) Attorney, Agent, or Firm — Sam Pierce

(**) Term: **15 Years**

(21) Appl. No.: **29/970,229**

(22) Filed: **Oct. 28, 2024**

(57) **CLAIM**

(30) **Foreign Application Priority Data**

Sep. 3, 2024 (CN) 202430561413.1

(51) **LOC (15) Cl.** **10-04**

DESCRIPTION

(52) **U.S. Cl.**

USPC **D10/81; D10/78**

(58) **Field of Classification Search**

USPC D10/78, 81

CPC G01N 27/4166; G01N 27/4167; G01N
21/80; G01N 31/22; G01N 31/221; G01N
21/78; A61B 5/145; A61B 5/14539
